UNITED STATES PATENT OFFICE.

CHARLES D. MOORE, OF WHITE SALMON, WASHINGTON.

CONVERTIBLE AUTOMOBILE FURNITURE.

1,408,708.

Specification of Letters Patent.

Patented Mar. 7, 1922.

Application filed April 18, 1921. Serial No. 462,277.

To all whom it may concern:

Be it known that I, CHARLES D. MOORE, a citizen of the United States, residing at White Salmon, in the county of Klickitat, 5 State of Washington, have invented certain new and useful Improvements in Convertible Automobile Furniture; and I do hereby declare the following to be a full, clear, and exact description of the invention, such as 10 will enable others skilled in the art to which it appertains to make and use the same.

This invention relates to new and useful improvements in furniture and particularly to convertible furniture for use in connection with automobiles.

One object of the invention is to provide a piece of furniture which is adapted to be used as a table, and in connection with which are associated four seats arranged at 20 the four sides of the table.

Another object is to provide a device of this character which may be so folded as to provide a bench or benches.

A further object is to provide a device of 25 this character which is adapted to be separated to form, in conjunction with the running-boards of an automobile, a pair of beds, on which are adapted to be placed cushions.

A still further object is to provide a device of 30 this character which can be folded into a small and compact condition which will readily lie on one of the running-boards of the automobile.

Other objects and advantages will be apparent from the following description when 35 taken in connection with the accompanying drawings.

In the drawings:

Figure 1 is a perspective view of the 40 convertible furniture in the position of a table and four seats.

Figure 2 is a perspective view of the device in folded position.

Referring particularly to the accompanying 45 drawing, 10 and 11 represent a pair of boards of proper length, width, and thickness, the same being pivoted centrally by the bolt 12, to swing in horizontal planes, one above the other, whereby when folded for 50 storage, the board 11 will lie directly beneath the board 10, as clearly seen in Figure 2 of the drawing.

The side portions of each end of the board 10 are cut away, as shown at 13, and hinged 55 to each of the longer edge portions of the intermediate part of the said board, is a leaf

board 14, and to the outer longer edge portion of each leaf board 14 is hinged a second leaf board 15. The leaves 14 are so hinged that they may be folded over on top of the 60 board 10, and the leaves 15 are so hinged to the leaves 14 that they may be folded over on top of the leaves 14. The width of each leaf is such that they occupy one half of the width of the board 10 when folded 65 over thereon, while their lengths are equal to the length of the intermediate or wider portion of the board.

The lower board 11 has the keyhole opening 16 in its center so that the board may 70 be readily detached from the board 10 without the necessity of removing the pivot bolt 12.

At each end of each board 10 and 11 is disposed a frame including a pair of legs 17, 75 each of a width and length to perfectly fit in a cut away 13. The upper ends of the legs are connected in pairs, by the reinforcing straps 18, while similar straps 19 are secured to the lower portions of the legs. It 80 will be noted that the straps 18 are secured to the upper ends of the legs, while the straps 19 are secured to the outer faces of the legs. By this arrangement, when the legs are in folded position, as shown in Figure 2, the straps 18 lie outwardly of the ends of the boards, while the straps 19 lie against the lower faces of the ends thereof.

Extending transversely through each pair of legs, and through the end of the board, is 90 a bolt 20, whereby the legs are pivotally connected to the board for swinging movement into and out of folded position.

Pivotally connected to each of the legs 17 is a break joint brace 21, the other end of 95 which lies against one side edge of the end portion of a board.

Figure 1 clearly shows the use of the device as a table, the boards 10 and 11 being disposed in right angular crossed relation, 100 and with the leaves unfolded and resting on the board 11. The portions of the board 11, which project beyond the outer leaves 15, serving as seats for two persons, while the end portions of the board 10, which project 105 beyond the ends of the leaves 14 and 15, serve as two additional seats. Thus there is provided a table with four seats. When not in use, the leaves are folded over into the position shown in Figure 2, and the boards 110 swung around to lie in superimposed relation, after the pairs of legs have been swung

upwardly into the cut outs 17 of the board 10 and at the sides of the board 11. In the inner edge face, of the upper end portion of each leg there is formed a recess 23 into which the brace 21 fits, when the leg is in folded position.

The boards 10 and 11 may be separated from each other and each used as a bench, the leaves of the board 10 being first folded 10 onto the board.

Also, each board may be set up at the side of one of the running-boards of the automobile, and cushions placed on the running-boards and the boards 10 and 11, to form 15 comfortable beds.

When completely folded, the device is adapted to be placed on one of the running-boards of the automobile, and being of a length and width, when so folded, as to occupy 20 very little space.

What is claimed is:

1. A device of the class described comprising a pair of pivoted members one of which carries foldable leaves forming in conjunction with the member a table top, and ar- 25

ranged to lie transversely on the other member, foldable legs carried by each end of a member, each end of each member extending beyond the table top to form seats, said legs being arranged to be folded to lie in the 30 planes of the members and inwardly of the sides thereof.

2. A device of the class described comprising a pair of benches arranged to be disposed in crossed relation, the ends of the 35 benches forming seats, leaves hinged to the intermediate portions of the longer edges of one of the benches and adapted to be extended to lie on the other bench inwardly of the seats thereof, the opposite ends of the 40 benches being formed with recesses, and supporting legs pivotally carried by the bench ends and foldable into the recesses.

In testimony whereof, I affix my signature, in the presence of two witnesses.

CHARLES D. MOORE.
